DOOR CLOSER

Ernest L. Schlage, Burlingame, Calif., assignor
to Schlage Lock Company, a corporation

Application January 19, 1953, Serial No. 23,178

Term of patent 14 years

(Cl. D10—7)

To all whom it may concern:

Be it known that I, Ernest L. Schlage, a citizen of the United States, residing at Burlingame, county of San Mateo, and State of California, have invented a new, original, and ornamental Design for a Door Closer, of which the following is a specification, reference being had to the accompanying drawing, forming a part hereof.

Fig. 1 is a front perspective view of a door closer with the actuating arm broken away and showing my new design;

Fig. 2 is a top plan view of the door closer of Fig. 1;

Fig. 3 is a front elevational view of the door closer of Fig. 1; and

Fig. 4 is an end elevational view of the door closer of Fig. 1.

I claim:

The ornamental design for a door closer, as shown.

ERNEST L. SCHLAGE.
